CUTOFF MACHINE TRIPPING MECHANISM

John R. Rosenleaf and Emmett D. Benham,
Enterprise, Kans., assignors to The J. B.
Ehrsam & Sons Manufacturing Company,
Enterprise, Kans., a corporation of Kansas

Application September 2, 1941, Serial No. 409,214

21 Claims. (Cl. 164—66)

It is the primary object of the present invention to simplify the construction and control of cut-off machines particularly of the type primarily intended for use upon plaster board and the like and in which it is often desirable to cause the machine to sever the work upon one revolution and to perforate the work upon another revolution. The machine of the present invention is likewise capable of cutting or perforating the work at intervals which are not even multiples of the circumference of the knife orbits. A further object of the invention is to provide, in a machine of the character here under consideration and having a plurality of knives mounted on a continuously operating rotor, means for automatically preventing damage to the work by contact with those knives during non-active periods of the machine, while insuring against bending of the work under the influence of the knives at the time of coaction of the knives to cut or perforate the work.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is an elevation of the machine of the present invention;

Fig. 2 is an elevation taken from the left-hand end of Fig. 1;

Fig. 3 is a section taken substantially on the line 3—3 of Fig. 1 and looking in the direction of the arrows;

Fig. 4 is a fragmental section taken substantially on the line 4—4 of Fig. 1 and looking in the direction of the arrows; and

Fig. 5 is an elevation, upon an enlarged scale, of the left-hand end of Fig. 1.

Referring more particularly to the drawings, it will be seen that we have illustrated a machine very similar in many respects to the machine disclosed in our Patent 2,288,921 issued July 7, 1942; but that, in the present disclosure, the transaxially-shiftable rotor carries only one knife, the fixed-axis rotor is continuously driven, the trip mechanism for connecting the first-mentioned rotor to be driven is quite different, and the driving train and control for the rotor-shifting cam is different. Too, in the present disclosure, we have provided a work-supporting

cradle, shiftable in accordance with the operation of the upper rotor, and finding no counterpart in our said patent.

In Figs. 1 and 5 there will be seen the machine bed 10 mounted on feet 11 and supporting end frames 12 and 13 in which the ends 14 and 15 of lower rotor 16 are solidly journaled. The rotor 16 carries four knives 17, 18, 19, and 20, spaced 90° apart on its periphery.

One or more brackets 21 provide support for a countershaft 22 to which is keyed sprocket 23 driven by chain 24 from sprocket 25 on, for instance, the spindle 26 of a motor 27. Said countershaft 22 carries a pinion 28 meshing with a gear 29 carried on a continuation 30 of the end 14 of rotor 16, to provide a solid continuous drive for the rotor 16.

A continuation 31 of the end 15 of the rotor 16 is journaled in a supplemental end frame 32 mounted on the bed 10, and carries a gear 33 continuously meshing with a gear 34 of equal pitch diameter mounted on a stub shaft 35 journaled in the frame member 32. To one face of the gear 34 is secured one member 36 of an "Oldham" coupling of well-understood construction, while the mating element 37 of said coupling has secured to its outer face a jaw clutch element 38. The elements 37 and 38 are loosely mounted on a projection 39 of one end 40 of an upper rotor 41, the ends 40 and 42 of said rotor being journaled in suitable bearings in bearing carriages slidably mounted respectively in the end frames 12 and 13 in the manner illustrated in Fig. 3.

As is clearly shown in Figs. 1, 3, and 5, the end 40 of rotor 41 is journaled in a slide plate 43 guided for vertical movement in a guideway 44 formed in the end frame 13, said plate being supported by a spring 45. The opposite end 42 of said rotor is similarly mounted, so that said rotor is transaxially shiftable toward and away from the rotor 16.

Integral with, or fixedly secured to, the plate 43 is a platform 46, formed to provide two hinge lugs 47, 47, in which is received a pintle 48 to which are fixed a pair of yoke arms 49, 49 provided with shoes 50, 50 diametrically oppositely received in an annular groove 51 formed in a clutch element 52 fixed on extension 39 and adapted to mate with clutch element 38. At least one of said arms is provided with an extension 53 with which is associated a coiled spring 54 urging said yoke arms to swing in a counter-clockwise direction; as viewed in Figs. 1 and 5, to move said clutch element 52 into cooperative

relation with the element 38; but said element 52 is normally restrained against such movement and held in the position illustrated in Figs. 1 and 5 by the engagement of a trip dog 55 with the thickened portion 56 of an annular cam collar 57 integral with or fixed to said element 52.

As is clearly shown in Figs. 1, 3, and 5, the dog 55 is reciprocably mounted in a lug 58 carried on said platform 46, and is held in position by a finger 59 on a rockshaft 60 journaled in bearings 61, 61 depending from the platform 46, and carrying a lever 62 with which is associated a coiled spring 63 tending to rotate said lever in a clockwise direction as viewed in Figs. 1 and 5, and thereby holding the dog 55 in its illustrated position.

It will be obvious that the driving train thus far described will produce continuous rotation of the rotor 16, and will effect rotation of the rotor 41 only when the clutch element 52 is engaged with the clutch element 38; and that the provision of the "Oldham" coupling permits the transmission of movement from the stub shaft 35 to the rotor 41 whether or not those members are in axial alignment. A single knife 64 is carried by the rotor 41.

In the illustrated positions of the parts, the dog 55 cooperates with the thickened portion 56 of the cam collar 57 to hold the clutch element 52 out of engagement with the element 38. Counterclockwise movement of the lever 62, however, in opposition to the spring 63, will withdraw the dog 55 to permit the spring 54 to move the element 52 into cooperative relation with the constantly rotating element 38 to drive the element 52 and the rotor 41. If the lever 62 is now promptly released, the spring 63 will urge the dog 55 into engagement with the peripheral surface of the collar 57 of the rotating element 52; and as said element rotates, the thin portion of the collar will come into registry with the dog 55 to permit said dog to move upwardly into contact with the left-hand, cammed face of said collar. Thus, as the rotor 41 approaches completion of a revolution, the dog 55, acting on the cammed face 56 of the collar 57, will shift the element 52 to the right to disengage said element from the element 38. Preferably, a spring-pressed brake 65 is associated with a projecting portion of the end 42 of the rotor 41 to stop said rotor promptly upon disengagement of said clutch elements, the brake 65 being mounted to partake of the transaxial movement of the rotor 41.

Beyond the supplemental end frame 32, the extension 31 carries a bevelled gear 66 meshing with a gear 67 fixed on a shaft 68 journaled in suitable brackets 69 and 70. The shaft 68 carries a sprocket 71 connected, by a chain 72 to drive a double sprocket 73, 74 suitably journaled on the machine frame. The chain 72 engages the portion 73 of the last-named sprocket; and a control chain 75 hangs loosely on the sprocket portion 74, said chain 75 carrying one or more suitably positioned trip elements 76. It will be clear from the above that the chain 75 is driven with the continuously rotating rotor 16, and, at predetermined points in the cycle of the rotor 16, a trip element 76 will be caused to engage the lever 62 to swing the same in a counterclockwise direction to withdraw the dog 55 to permit engagement of the clutch element 52 with the element 38, and that thereupon the rotor 41 will be turned through one revolution, upon the completion

of which the now-released dog 55 will cause disengagement of the element 52 from the element 38, and the brake 65 will stop the rotor 41.

Of course, the chain 75 will be so associated with the sprocket 74 as to trip the clutch mechanism at a time such as to bring the knife 64 into vertically downwardly directed position at a time to cooperate with one of the knives on the rotor 16. It will be obvious that the chain 75 can be so designed and proportioned as to cause the knife 64 to cooperate with any one of the knives on the rotor 16 upon each revolution of the rotor 16, or to cooperate with successive knives on the rotor 16. Thus, depending upon the selection of a chain 75 of suitable length or with suitably spaced trip elements 76, the rotor 41 can be caused to make one revolution for each revolution of the rotor 16, or one revolution for each one and one-fourth revolutions of the rotor 16, or one revolution for each one and one-half revolutions of the rotor 16, or one revolution for each one and three-fourths revolutions of the rotor 16, or one revolution for any other number of revolutions of the rotor 16 in the same arithmetical progression. Thereby, the machine can be caused to cut material traveling therethrough to any desired length greater than the periphery of the orbit of the knives on the rotor 16 by any desired multiple of one-fourth that length.

It is often desirable, particularly in working upon plaster board, to cause a cut-off machine to perforate the board at stated intervals between severing operations. It is for that reason that the rotor 41 is mounted for transaxial movement relative to the rotor 16, and we have provided means for automatically shifting the rotor 41 between that position in which the knife 64 will cooperate with one of the knives on the rotor 16 to sever the board and that position in which the knife 64 will cooperate with one of the knives on the rotor 16 merely to perforate the board without severing it. Referring, again, to Fig. 3, it will be seen that the slide plate 43 mounts a roller 77 adjacent its upper end, and that a cam 78 engages said roller to hold the slide plate 43 down against the tendency of the spring 45. It will be obvious of course that the other end 42 of the rotor 41 is journaled in a similar slide plate provided with a similar roller with which cooperates a similar cam which is carried on the same cam shaft 79 with the cam 78.

On the countershaft 22 is fixed a sprocket 80 which drives, through a chain 81, a sprocket 82 fixed on a tubular shaft 83 suitably journaled in the end frames 33 and 32. Fixed to the shaft 83 is a clutch member 84 very similar to the member 52, and similarly provided with a cam collar 85 having a thickened portion 86, and with an annular groove 87. Yoke arms 88, 88 are mounted upon a suitable rock shaft 89 journaled upon a bracket 90 carried by the end frame 32, and said arms are received in the groove 87. At least one of said arms is formed with an extension 91 with which cooperates a coiled spring 92 urging the yoke arms to swing in a counterclockwise direction. Reciprocably mounted in the bracket 90 is a trip dog 93 cooperating with the collar 85 normally to hold the clutch element 84 in the illustrated position. Likewise journaled in the bracket 90, and in an additional bearing 94, is a rock shaft 95 to which is fixed a lever 96 engaging the dog 93, said shaft being resiliently held, by means of a spring 97, in the illustrated position. A lever 98 fixed to the shaft 95, is disposed in the path of trip elements 99 carried by

a chain 100 supported on a double sprocket 101, 102 driven, by a chain 103 from a sprocket 104 on the shaft 68.

A clutch element 105 is mounted upon a shaft 106 concentric with the shaft 83. When the lever 96 is tripped, the dog 93 will be withdrawn to permit the clutch element 84 to engage the clutch element 105 to drive the shaft 106 through a single revolution, upon the completion of which, the dog 93, cooperating with the thickened portion 86 of the cam collar 85, will disengage the element 84 from the element 105. A sprocket 107 on the shaft 106 is connected by a chain 108 to drive sprocket 109 on the cam shaft 79.

It is here to be noted that the gear ratio between the pinion 28 and gear 29 is one to two, so that two revolutions of the countershaft 22 will produce one revolution of the rotor 16; the gear ratio between the sprocket 80 and the sprocket 82 is one to two, so that two revolutions of the countershaft 22 will produce one revolution of the tubular shaft 83; and the gear ratio between the sprocket 107 and 109 is one to two, so that two revolutions of the countershaft 22 will produce one-half revolution of the cam shaft 79. Thus, each time the lever 98 is tripped, the cam shaft 79 will be turned through one-half revolution. Thus, if the trip elements 99 are so arranged as to trip the lever 98 each time the lever 62 is tripped, the machine will sever the work upon odd revolutions of the rotor 41, and will perforate the work upon even revolutions of the rotor 41. Alternatively, of course, the stops 99 may be so set on the chain 100 as to cause the machine to sever any desired number of times between severing operations, or to sever any desired number of times between perforating operations.

Because the rotor 16 with its four knives is continuously rotating, it is desirable to elevate the work normally into a plane outside the orbit of the knives on the rotor 16, so that said knives shall not mutilate or scar the work between the points at which the machine severs or perforates the work. On the other hand, it is undesirable to hold the work outside the orbit of the knives on the rotor 16 during severing or perforating operations, because if the work were so supported, the effect of the knife 64 would be to bend the work downwardly, between the points of support, and into the orbit of the knives on the rotor 16. Therefore, we have provided a cradle for the work comprising idle rollers 110 and 111 supported in a frame work 112, and positioned on opposite sides of the vertical plane including the axes of the rotors 16 and 41. The frame 112, in turn, is supported upon a frame comprising uprights 113 and 114, an upper cross bar 115, and a lower cross bar 116. A two-part slide 117 is reciprocably mounted between the frame elements 113 and 114, being held in adjusted position therein between bolts 118 and 119, said bolts being operable to adjust the position of the frame 112 with respect to the end 42 of the rotor 41. Suitably fixed to the rotor end 42, and rotatable within the slide 117, is an eccentric ring 120. It will be seen that rotation of the rotor end 42 and the ring 120 will cause reciprocation of the cradle with its rollers 110 and 111, with respect to the axis of the rotor 41. The opposite end of the cradle is similarly supported by a frame work 121 associated with the end 40 of the rotor 41; and legs 122 are secured to element 112 and slidably engage the uprights of the frame member 12.

When the rotor 41 is in the position illustrated,

the eccentric ring 120 will be in the position illustrated in Fig. 4, in which the rollers 110 and 111 will be at their minimum distance below the axis of the rotor 41, and in which position, work supported upon the rollers 110 and 111 will be disposed outside the orbit of the knives on the rotor 16. As the rotor 41 is rotated, the cam ring 120 will be rotated therewith; so that, as the knife 64 approaches a vertically downward position, the frame 112 will be moved downwardly with respect to the rotor 41, whereby the upper surfaces of the rollers 110 and 111 will fall below the horizontal plane tangent with the orbit of the knives on the rotor 16, so that it will be unnecessary for the knife 64 to bend the work downwardly into engagement with the cooperating knife on the rotor 16. As the knife 64 moves beyond its vertically downward position, the eccentric ring 120 will begin to elevate the frame 112, and the work will be moved out of the orbit of the knives on the rotor 16 before the next adjacent knife on said rotor comes into a vertically upward position.

It will be obvious that the minimum length of material which can be cut with the present machine is determined by the periphery of the orbit of the cutting edge of the knife 64. In practice, this length is usually 48 inches. Since the rotor 16 is provided with four knives, equally spaced, it will be obvious that the machine is capable of cutting lengths greater than 48 inches by any desired multiple of 12 inches.

Because the clutches 38, 52, and 84, 105 are four-jaw clutches, it is possible to trip the machine at any time within one quarter of a revolution of the desired cutting position, and still get an accurately positioned cut, because the rotor 41 or the cam shaft 79 will not start to move until the completion of the quarter revolution during which the machine is tripped.

It is our present belief that the trip mechanism including the chain 75 and the lever arm 62 will operate satisfactorily and with sufficient accuracy, even though the sprocket 74 is mounted upon a fixed axis, while the lever 62 moves somewhat in a vertical direction. Of course it will be obviously possible, without invention, to support the double sprocket 73, 74 from the platform 46, providing any suitable means, such, for instance, as a resiliently biased idler sprocket, to compensate, in the chain 72, for variations in the center distance between the shaft 68 and the sprocket 74 resulting upon such modification.

We claim as our invention:

1. A cut-off machine comprising a pair of knife-carrying rotors, a plurality of knives carried by one of said rotors, a single knife carried by the other of said rotors, and means for driving said rotors, including means for selectively disconnecting said last-named rotor from said driving means and reconnecting the same in timed relation to cause said single blade to cooperate with any one of said plurality of blades.

2. A cut-off machine comprising a pair of knife-carrying rotors, a plurality of knives carried by one of said rotors, a single knife carried by the other of said rotors, means for transaxially shifting one of said rotors, and means for driving said rotors, including means for selectively disconnecting said last-named rotor from said driving means and reconnecting the same in timed relation to cause said single blade to cooperate with any one of said plurality of blades.

3. A cut-off machine comprising a pair of knife-carrying rotors, a plurality of knives carried by one of said rotors, a single knife carried

by the other of said rotors, means for transaxially shifting one of said rotors, and means for driving said rotors, including means for selectively disconnecting said last-named rotor from said driving means and reconnecting the same in timed relation to cause said single blade to cooperate with any one of said plurality of blades, and means for varying the cycle of said shifting means.

4. In a cut-off machine, a lower rotor, at least one knife on said rotor, means for continuously driving said rotor, an upper rotor, at least one knife on said upper rotor, means for driving said upper rotor, means for varying the center distance between said rotors, a work support arranged between said rotors and adapted normally to support work out of cooperative relation with said knives, and means dominated by said center distance varying means for shifting said work support toward one of said rotors upon reduction in such center distance.

5. In a cut-off machine, a lower rotor, at least one knife on said rotor, means for continuously driving said rotor, an upper rotor, at least one knife on said upper rotor, means for shifting one of said rotors toward and away from the other of said rotors, a work support arranged between said rotors and adapted normally to support work out of cooperative relation with said knives, and eccentric means on said upper rotor supporting said work support for transaxial movement with respect to both of said rotors.

6. In a cut-off machine, a lower rotor, at least one knife on said rotor, means for continuously driving said rotor, an upper rotor, at least one knife on said upper rotor, means for shifting one of said rotors toward and away from the other of said rotors, a cradle formed to provide a rest over which work may move between said rotors, eccentric means associated with said upper rotor and supporting said cradle, said eccentric means being transaxially shiftable with said upper rotor to shift said cradle transaxially with respect to said lower rotor, and rotatable with said upper rotor to shift said cradle transaxially with respect to said upper rotor.

7. In a cut-off machine, a first knife-carrying rotor, means for continuously driving said rotor, a second knife-carrying rotor, means for intermittently driving said second rotor, a work support arranged between said rotors and adapted normally to support work out of contact with the knives of both rotors, and automatic means for shifting said work support, when said second rotor is driven, to bring work supported thereon within the paths of the knives of both rotors.

8. In a cut-off machine, a fixed-axis rotor, at least one knife carried by said rotor, means for continuously driving said rotor, a second rotor, at least one knife carried by said second rotor, means for intermittently driving said second rotor, means for transaxially shifting said second rotor, a work support arranged between said rotors and adapted normally to support work outside the path of any knife carried on said lower rotor, and automatic means for shifting said work support, when said second rotor is driven, into a position in which work supported thereon is disposed within the paths of the knives of both rotors.

9. In a cut-off machine, a first rotor, a plurality of knives carried thereon, means for driving said first rotor, a second rotor, a single knife carried on said second rotor, a drive train for said second rotor including a single-revolution clutch, and means driven with said first rotor for

tripping said clutch at a predetermined point in the cycle of said first rotor.

10. In a cut-off machine, a first rotor, a plurality of knives carried thereon, means for driving said first rotor, a second rotor, a single knife carried on said second rotor, a drive train for said second rotor including a single-revolution clutch, and means driven with said first rotor and operable to trip said clutch at any of a plurality of predetermined points in the cycle of said first rotor.

11. In a cut-off machine, a fixed-axis rotor, at least one knife carried by said rotor, means for continuously driving said rotor, a second rotor, at least one knife carried by said second rotor, means for intermittently driving said second rotor, means for transaxially shifting said second rotor, a work support arranged between said rotors and adapted normally to support work outside the path of any knife carried on said lower rotor, and automatic means for shifting said work support, when said second rotor is driven, into a position in which work supported thereon is disposed within the paths of the knives of both rotors, said last-named means being alternatively operable to cause said one blade on said second rotor to coact with any one of said plurality of blades on said first rotor.

12. In a cut-off machine, a first rotor, a plurality of knives carried thereon, means for driving said first rotor, a second rotor, a single knife carried on said second rotor, a drive train for said second rotor including a single-revolution clutch, means driven with said first rotor for tripping said clutch periodically, means for mechanically varying the center distance between said rotors, including a rotary element, a drive train for said rotary element including a second single-revolution clutch, and means driven with said first rotor for tripping said second clutch.

13. In a cut-off machine, a first rotor, a plurality of knives carried thereon, means for driving said first rotor, a second rotor, a single knife carried on said second rotor, a drive train for said second rotor including a single-revolution clutch, means driven with said first rotor for tripping said clutch periodically, means for mechanically varying the center distance between said rotors, including a rotary element, a drive train for said rotary element including speed reducing mechanism and further including a second single-revolution clutch, and means driven with said first rotor for tripping said second clutch.

14. In a cut-off machine, a first rotor, a plurality of knives carried thereon, means for driving said first rotor, a second rotor, a single knife carried on said second rotor, a drive train for said second rotor including a single-revolution clutch, means driven with said first rotor for tripping said clutch periodically, means for mechanically varying the center distance between said rotors, including a rotary cam cooperating with one of said rotors and having one position in which the orbits of the knives on the two rotors intersect and a diametrically-opposite position in which the adjacent points in such orbits are separated but by a distance less than the thickness of the work being operated upon by the machine, a drive train for said cam including speed reducing mechanism designed to produce one-half revolution of said cam during one revolution of said first rotor and further including a second single-revolution clutch, and means driven with said first rotor for tripping said second clutch.

15. In a cut-off machine, a first rotor, a plurality of knives carried thereon, means for driving said first rotor, a second rotor, a single knife carried on said second rotor, a drive train for said second rotor including a single-revolution clutch, means driven with said first rotor for tripping said clutch periodically, means for mechanically varying the center distance between said rotors, including a rotary cam cooperating with one of said rotors and having one position in which the orbits of the knives on the two rotors intersect and a diametrically-opposite position in which the adjacent points in such orbits are separated but by a distance less than the thickness of the work being operated upon by the machine, a drive train for said cam including speed reducing mechanism designed to produce one-half revolution of said cam during one revolution of said first rotor and further including a second single-revolution clutch, and means driven with said first rotor and operable to trip said second clutch at any of a plurality of predetermined points in the cycle of said first rotor.

16. In a cut-off machine, a first rotor, a plurality of knives carried thereon, means for driving said first rotor, a second rotor, a single knife carried on said second rotor, a drive train for said second rotor including a single-revolution clutch, means driven with said first rotor and operable to trip said clutch at any of a plurality of predetermined points in the cycle of said first rotor to cause said one blade on said second rotor to coact with any one of said plurality of blades on said first rotor, means for mechanically varying the center distance between said rotors, including a rotary cam cooperating with one of said rotors and having one position in which the orbits of the knives on the two rotors intersect and a diametrically opposite position in which the adjacent points in such orbits are separated but by a distance less than the thickness of the work being operated upon by the machine, a drive train for said cam including speed reducing mechanism designed to produce one-half revolution of said cam during one revolution of said first rotor and further including a second single-revolution clutch, and means driven with said first rotor and operable to trip said second clutch at any of a plurality of predetermined points in the cycle of said first rotor.

17. In a cut-off machine, a fixed-axis rotor, a plurality of knives carried on said rotor, means for continuously driving said rotor, a second rotor, a single knife carried on said second rotor, a drive train for said second rotor including a single-revolution clutch, means driven with said first rotor and operable to trip said clutch at any

of a plurality of predetermined points in the cycle of said first rotor, means for transaxially shifting said second rotor, including a rotary cam cooperating with said second rotor and having one position in which the orbits of the knives on the two rotors intersect and a diametrically opposite position in which the adjacent points in such orbits are separated but by a distance less than the thickness of the work being operated upon by the machine, a drive train for said cam including a second single-revolution clutch, and means driven with said first rotor and operable to trip said second clutch at any of a plurality of predetermined points in the cycle of said first rotor, a work support arranged between said rotors and adapted normally to support work outside the orbit of the knives on said lower rotor, and automatic means for shifting said work support, when said first clutch is tripped, into a position in which work supported thereon is disposed within the orbits of the knives on both rotors.

18. A cut-off machine comprising a pair of knife-carrying rotors, a plurality of knives carried by one of said rotors, a single knife carried by the other of said rotors, means for cyclically transaxially shifting one of said rotors in a predetermined relation to the cycle of operation of said other rotor, and means for varying said relation to bring said one knife selectively into coaction with any one of said plurality of knives.

19. In a cut-off machine, a first knife-carrying rotor, means for continuously driving said rotor, a second knife-carrying rotor arranged in cooperative relation with said first rotor, and means for intermittently driving said second rotor to cause rotation thereof in any desired one of a plurality of phase relations to said second rotor.

20. In a cut-off machine, a first rotor, a plurality of knives carried thereon, means for continuously driving said first rotor, a second rotor, a single knife carried on said second rotor, a driving train for said second rotor only, including a single-revolution clutch, and means driven in synchronism with said first rotor for tripping said clutch at a predetermined point in the cycle of said first rotor.

21. In a cut-off machine, a first rotor, a plurality of knives carried thereon, means for driving said first rotor, a second rotor, a single knife carried on said second rotor, a drive train for said second rotor including a single-revolution clutch, and means operable to trip said clutch at any of a plurality of predetermined points in the cycle of said first rotor.

JOHN R. ROSENLEAF.
EMMETT D. BENHAM.
